UNITED STATES PATENT OFFICE.

STEPHEN J. CLULEE, OF ATTLEBOROUGH, MASSACHUSETTS, ASSIGNOR TO THE BAY STATE OPTICAL COMPANY, OF SAME PLACE.

DESIGN FOR AN EYEGLASS-HOOK.

SPECIFICATION forming part of Design No. 25,603, dated June 9, 1896.

Application filed March 18, 1896. Serial No. 583,818. Term of patent 7 years.

To all whom it may concern:

Be it known that I, STEPHEN J. CLULEE, a citizen of the United States, residing at Attleborough, in the county of Bristol and State 5 of Massachusetts, have invented and produced a new and original Design for Eyeglass-Hooks, of which the following is a specification, reference being had to the accompanying drawing, forming part thereof.

10 The drawing is a perspective view of an eyeglass-hook, showing my design.

The leading feature of my design consists in two round beads parallel to each other, which form the lower bent portion of the 15 hook and terminate into a long open loop forming flat marginal edges.

In the drawing the round shaft 3, terminating at its lower end into the point 4, extends at its upper end into the loop 5, of 20 greater transverse width than the diameter of the shaft 3. The loop on the descending side gradually diminishes in width and joins the outwardly-curved round bar 6, the lower end of which enters the scroll 7, which extends around the bar 6 and around the lower 25 part of the shaft 3. Below the loop 7 the beads 8 and 9 form the two edges of the hook 10 and extend upward to the point 11, where the beads 8 and 9 terminate in the flattened marginal borders of the open loop 13, uniting 30 at the upper end above the open loop 13, thus presenting to the eye the appearance of an open leaf-like figure, of which the line 15, between the round beads 8 and 9, forms the stem. 35

Having thus described my newly-produced design, I claim as new and desire to secure by Letters Patent—

The design for an eyeglass-hook herein shown and described. 40

In witness whereof I have hereunto set my hand.

STEPHEN J. CLULEE.
